HENRY P. ROBERTS, OF BROOKLYN, NEW YORK, ASSIGNOR TO DICTAPHONE CORPORATION, OF BRIDGEPORT, CONNECTICUT, A CORPORATION OF NEW YORK.

RECORD-RESURFACING MACHINE.

Application filed July 28, 1925. Serial No. 46,577.

This invention relates to machines for shaving or resurfacing phonograph record blanks for preparing the surface of such blanks for use.

5 An object of the invention is to provide means for preventing improper resurfacing of a record blank, due to irregularities in parts of the machine which tend to cause vibrations which would ultimately be transmitted to the resurfacing tool.

10 Another object of the invention is to simplify the cost of manufacture of the device by making it less imperative that the parts accurately fit, that is, by avoiding extremely small tolerances in the manufacture of the various parts.

Other objects and advantages will herein-after appear.

In the accompanying drawing, which shows 20 by way of example one embodiment of this invention, that at present preferred,

Figure 1 is a top plan view of a record shaving machine showing the present invention as embodied therein.

25 Fig. 2 is a side elevation of a portion of the machine shown in Fig. 1, showing the record mandrel and the record blank, and parts of the frame in section.

Fig. 3 is a perspective view of part of the 30 feed-nut mounting means.

Fig. 4 is a perspective view of the feed-nut and part of its mounting.

As shown in the accompanying drawing, the shaving machine preferably comprises a 35 base 10 upon which is rotatably mounted a record mandrel 11 secured to a shaft 12 having a pulley 13 connected with a motor, not shown, through a belt 14.

Also connected to the mandrel shaft 12 is 40 a pulley 15 connected by a belt 16 to a pulley 17 secured to a feed-screw shaft 18 journaled in the frame of the machine to the rear of the mandrel 11.

The record surface is adapted to be shaved, 45 burnished or resurfaced by means of a knife or other tool 19 adjustably mounted in a guide 20 secured to, or preferably forming part of, a carriage 21 which is mounted upon a guide rod 22 to travel longitudinally of the 50 mandrel and the record supported thereby.

The carriage 21 is held in proper operating position by means of a weighted arm 23, which has a lower guide arm 24 formed integral therewith, and normally resting and

sliding upon a rail 25 at the front of the 55 base 10.

For the purpose of causing the carriage to travel longitudinally, that is, in the direction toward the pulley 13 as seen in Fig. 1, so that the knife or other tool may move over the record surface, the carriage 21 is provided with a feed-nut 26 adapted to engage the feed-screw 18.

Heretofore, this feed-nut has been mounted upon a spring, or other resilient member, 65 rigidly secured to the carriage so that the feed-nut might move in a plane common to that of the axis of the feed-screw to accommodate itself to irregularities in the feed-screw thread. But, it has been found, in such de-

60 vices, that while the supporting device for the nut actually yields, it does, however, transmit vibrations to the carriage 21 and through it to the knife or other tool 19 with the result that irregularities or grooves are produced 70 upon the record surface, due to the transmission of such vibrations. It has also been found that a mounting member, which is

75 sufficiently resilient to prevent the transmission of such undesired vibrations, is too re- 80 sili ent to permit the carriage to travel properly with the feed-nut.

The present invention, however, has overcome these disadvantages by providing a support for the feed-nut 26 which is sufficiently 85 firm as to prevent skewing movement between the feed-nut and the carriage, and yet, which freely yields in a direction perpendicular to the axis of the feed-screw, and thus allows 90 the vibrations to be almost entirely absorbed by such yielding movements.

For this purpose, the feed nut 26 is securely 95 mounted on one arm 27 of a hinge, and the other arm 28 of which is securely fastened to the carriage 21 by means of screws 29.

Preferably, this hinge is formed by bending-up a pair of arms 30 on the part 27 and an arm 31 on the part 28 to form cylindrical sockets into which a bolt 32 is placed. But, of course, any other suitable form of 100 pivotal connection may be provided between the parts 27 and 28, so long as any appreciable skewing movement of the nut 26 with relation to the carriage is prevented, and so long as the part 27 moves freely in a vertical plane upon the part 28. Firm contact between the feed-nut 26 and the feed-screw 18 is 105 provided by connecting a spring 33 to one

end to the part 27, and at the other end to an arm 34 depending from the part 28. This spring normally tends to hold the feed-nut in positive engagement with the threads of the feed-screw, but allows the part 27, carrying the feed-nut, to move vertically to absorb the vibration due to irregular portions or bruises on the threads on the feed-screw 18.

When the carriage 21 reaches the limit of its movement when moving in the direction toward the pulley as seen in Fig. 1, that is to say, when the tool 19 has been moved beyond the inner end of the record blank, supported by the mandrel 11, no further movement of the carriage is permitted. To avoid damage being done to the threads of the screw or nut while the carriage is in this position during operation of the machine, the feed-screw 18 has a cut-away portion 35 to provide a smooth surface. Heretofore, the nut, upon engaging the cut-away portion 35 of the feed-screw, might ride upon the smooth surface, and while this was not particularly objectionable, yet the feed-nut would be worn somewhat by the abrasion thus produced between the tops of its teeth and the cut-away portion 35 of the feed-screw.

To avoid this wearing of the feed-nut, the present invention provides upon the part 27 which supports the feed-nut, a limit screw 36 whose lower end is adapted to engage the part 28 and hold the feed-nut from direct engagement with the cut-out portion 35 when the feed-nut has been moved to this portion of the feed-screw. Since the feed-nut is held in proper position by means of the spring 33 which freely yields, it is possible to allow the feed-nut threads to bottom on the threads of the feed-screw. Hence, the limit screw 40 may be, and preferably is, so adjusted as to permit this action. This is a decided advantage over devices heretofore provided, for in such devices it was necessary to so adjust the feed-nut or its mounting as to prevent the bottoming of the feed-nut on the feed-screw, which was a difficult and unsatisfactory adjustment to make.

To permit the adjustment of the feed-nut relatively to its mounting so that in spite of slight differences in the manufacture of the parts, the feed-nut may always be made to properly engage the feed-screw, the feed-nut 26 is secured upon the part 27 of the hinge by means of one or more screws 37 engaging the feed-nut and passing through elongated slots 38 in the part 27. To adjust the feed-nut, the screws 37 may be loosened and the feed-nut moved to proper position, which movement is allowed by the slots 38 until the feed-nut is in proper position, whereupon the screws 37 are again tightened to hold the feed-nut as adjusted.

To insure proper freedom of movement, there is necessarily some slight clearance between the carriage 21 and the guide rod 22

upon which it slides. The amount of clearance, of course, increases as the parts wear, and it has been found that the looseness thus produced may cause the knife, or other tool 19, to chatter, or otherwise improperly move during the operation of resurfacing a record blank with the result that an irregular surface may be produced on the record blank.

For the purpose of avoiding this, the invention provides a take-up device in the form of spring arms 39 (see Figs. 1 and 2), which are mounted on an extension 40 of the part 28 of the hinge for mounting the feed-nut 26. The ends 39 engage the guide rod 22, and are so located and arranged that their pressure upon the guide rod are sufficient at both ends 41 of the carriage so as to hold the carriage in proper position during its travel across the frame of the machine.

By mounting the spring arms 39 on the part 28 of the feed-nut mounting, the device of the present invention may be applied to new machines or preexisting machines as a unit and by the simple expedient of placing the device on the carriage in the same position and place as would be occupied by the device formerly used and then securing it to the carriage by two screws 29.

While I have shown the invention as applied to record resurfacing machines especially adapted for resurfacing cylindrical record blanks, it should be distinctly understood that the invention may also be used in machines for shaving or reconditioning flat record blanks.

It will also be understood that variations may be made within the scope of the invention and portions of the improvements may be used without others.

Having now described the invention, what is claimed as new, and for which it is desired to obtain Letters-Patent is:

1. In a device for resurfacing phonographic record blanks, a frame; a tool carriage mounted on the frame, a guide rod on the frame on which the carriage is pivotally mounted; a feed-screw on the frame; and a feed-nut mounted on the carriage and adapted to have free pivotal movement with relation to the carriage perpendicularly of the axis of the feed-screw and about an axis offset from the axis of the guide rod upon which the carriage is pivotally mounted.

2. In a device for resurfacing phonographic record blanks, a frame; a tool carriage mounted on the frame; a feed-screw mounted on the frame; a feed-nut for engaging the feed-screw; a pivoted arm mounted on the frame and adapted to carry the feed-nut; and a set-screw on the said arm adapted to engage the carriage to determine the position of the feed-nut with relation to the feed-screw.

3. In a device for resurfacing phonographic record blanks, a frame; a tool car-

riage mounted on the frame; a feed-screw mounted on the frame; a feed-nut for engaging the feed-screw; a pivoted arm mounted on the frame; and a tension spring for yieldingly holding the pivoted arm in position to cause the feed-nut to bottom upon the threads of the feed-screw.

4. In a device for resurfacing phonographic record blanks, a frame; a tool carriage mounted on the frame; a feed-screw mounted on the frame; a feed-nut for engaging the feed-screw; a hinge connection between the feed-nut and the carriage; and means for limiting the movement of the feed-nut toward the axis of the feed-screw.

5. In a device for resurfacing phonographic record blanks, a frame; a tool carriage mounted on the frame; a feed-screw mounted on the frame and having a cut-away portion at one end; a feed-nut for engaging the feed-screw adapted to travel to a position above the cut-away portion of the feed-screw; means for yieldingly urging the feed-nut towards the axis of the feed-screw to cause the feed-nut to engage a threaded portion of the feed-screw; and means for preventing the feed-nut from engaging the cut-away portion of the feed-screw.

6. In a device for resurfacing phonographic record blanks, a frame; a tool carriage mounted on the frame; a feed-screw mounted on the frame and having a cut-away portion at one end; a feed-nut for engaging the feed-screw adapted to travel in position above the cutaway portion of the feed-screw; means for yieldingly urging the feed-nut towards the axis of the feed-screw to cause the feed-nut to engage a threaded portion of the feed-screw; and means for limiting the movement of the feed-nut towards the axis

of the feed-screw so as to prevent threads of the feed-nut from engaging the cut-away portion of the feed-screw.

7. In a device for resurfacing phonographic record blanks, a frame; a tool carriage mounted on the frame; a feed-screw mounted on the frame; a feed-nut for engaging the feed-screw; and means for supporting the feed-nut in position to engage the feed-screw comprising a part detachably mounted on the carriage and a part attached to the feed-nut, said parts being hinged together.

8. In a device for resurfacing phonographic record blanks, a frame; a carriage mounted on the frame for travelling movement; a guide rod upon which the carriage slides; and resilient means for automatically taking up looseness between the carriage and the guide rod.

9. In a device for resurfacing phonographic record blanks, a frame; a carriage mounted on the frame; a guide rod upon which the carriage slides; and automatic means for taking up wear between the guide rod and carriage to hold the carriage firmly to the guide rod.

10. An attachment for phonographic record resurfacing machines comprising a hinge, one part of which may be attached to the carriage slidably mounted on a guide rod and the other part of which is attached to a feed-nut; and means on the first-named part for taking up looseness between the carriage and the guide rod.

Signed at New York, in the county of New York and State of New York, this 22nd day of July 1925.
